UNITED STATES PATENT OFFICE.

JOHN CHARLES WILLIAM STANLEY, OF SANTA CRUZ, CALIFORNIA, ASSIGNOR, BY
DIRECT AND MESNE ASSIGNMENTS, TO STANLEY PAPER FIBRE COMPANY, OF SAN
FRANCISCO, CALIFORNIA, A CORPORATION OF ARIZONA.

METHOD AND APPARATUS FOR DIGESTING WOOD AND OTHER FIBROUS MATERIALS.

1,075,795.

Specification of Letters Patent. Patented Oct. 14, 1913.

Application filed January 6, 1911, Serial No. 601,207. Renewed March 28, 1913. Serial No. 757,482.

To all whom it may concern:

Be it known that I, JOHN CHARLES WILLIAM STANLEY, a subject of the King of England, residing at Santa Cruz, in the

5 county of Santa Cruz and State of California, have invented new and useful Improvements in Methods and Apparatus for Digesting Wood and other Fibrous Materials, of which the following is a specification.

10 This invention relates to a digester for the cooking of wood, straw, flax and other material for the manufacture of pulp.

15 The object of this invention is to provide a digester for cooking wood, straw, flax and other fibrous material in large quantities; and to provide a digester involving details of construction designed to facilitate the feeding of the pulp into the digester; for 20 efficiently and effectually digesting the pulp and to facilitate its quick removal so as to produce a substantially continuous digestion of material to be rendered into pulp.

25 The invention consists of the parts and the construction and combination of parts, as hereinafter more fully described and claimed, having reference to the accompanying drawing, in which the figure is a vertical sectional view of the improved digester.

30 In the present embodiment of my invention I have shown the main body of the digester as comprising a vertically disposed cylinder which may be of any suitable dimensions and built of such material as to be 35 able to carry a pressure of from 80 to 125 pounds, more or less, and which is provided at its upper end with a truncated cone-shaped dome 2 and a similarly shaped bottom 3, each of which members are provided 40 with a steam tight door as 4 and 5. Through the upper one the material to be digested is charged into the digester after the same has been previously filled with a suitable solution of caustic soda, sulfate of 45 soda, or other appropriate material. The solution having been first heated in the digester to about the boiling point by the application of steam or other heated fluid which may be distributed through a vertical 50 manifold or pipe 6 from which extend a plurality of branches 7 connected by any appropriate device to the body A of the di-

gestor. Each of the several branches 7 is provided with a valve 8 through which the admission of fluid from the pipe 6 may be 55 admitted into the digester A.

For the purpose of insuring a thorough subjection of the material to be digested to the action of the solution in the digester there is centrally mounted therein a vertical, 60 perforated tube 9 which is connected by transverse or radially extending perforated pipes 10 to the connections 7 with the main supply pipe 6 of which there may be one provided on each side of the digester. To 65 the lower end of the perforated pipe 9 is connected a drain pipe 12 in which is mounted a control valve 13 which may be opened at the proper period to allow the fluid contents of the digester to drain therefrom 70 into a condensing coil or other appropriate apparatus, as indicated at 14.

There is connected to the dome 2 of the digester a supply pipe 15 adapted to convey air under pressure directly into the upper portion of the body A, the flow of the fluid through the pipe 15 being controlled by a suitable valve 16, and from the pipe 15 is led a connection 17 joining with the main steam pipe 6 at its upper end. A valve 18 is 80 provided in a pipe 19 which joins with the steam pipe 6 to control the admission of steam to the distributor 6.

The digester is operated in the following manner: Wood or other material to be 85 treated, and which has been reduced to a predetermined size, is charged through the top door 4 into the digester body A in sufficient quantities to be practically submerged in the solution previously supplied 90 to the digester and which has been heated to the boiling point by the admission of steam through the lower branches 7 connected to the distributor 6, thus allowing the heated fluid to be discharged through the 95 perforated pipes 9 and 10 into the volume of the solution in the digester. During the period when the heating medium is being applied to the liquor in the digester those branches 7 which are above the level of the 100 solution or liquor are closed at their valves 8 so that all the heating medium is directed into the lower portion of the digester, and at which time the valve 16 and the branch

17 connecting the air pipe 15 with the digester 6 is closed. The wood or other material to be digested is gradually filled in in a quantity predetermined in proportion to the volume of the solution, after which the manhole or cover 4 is closed and the contents cooked at from 80 to 100 pounds pressure for eight hours or such time as may be found necessary to reduce the same to pulp. When the cooking is completed the valve 13 connected to the lower end of the perforated pipe 9 is opened so as to allow the solution to drain off into the condensing coil 14, all of the valves 8 being closed and the valve 16 opened sufficient to allow a small quantity of compressed air to enter creating a pressure in the upper part of the digester slightly in excess of the steam pressure in the same which will result in the gradual discharge of the liquor in the perforating tube from which it will drain from the digester through the condenser coil 14. The valve 13 is then closed again and the digester filled with compressed air to a pressure of about 100 pounds so as to thoroughly collect all of the fluid in the pulp in the lower portion of the drain pipe 9 when the valve 13 may be again opened to permit the collected fluid to discharge through the coil 14, and this collecting operation may be repeated until the contents of the digester is sufficiently cool to permit the discharge of the pulp through the bottom door 5.

In order to facilitate the discharge of the cooked pulp from the digester and after the bottom door 5 has been opened, air under suitable pressure may be admitted into the cone top 2, thus effectively forcing downwardly the material in the digester and discharging it from the bottom opening at the door 5.

Having thus described my invention, what I claim and desire to secure by Letters Patent is—

1. The process herein described for the digestion of fibrous material, said process consisting in immersing the material in a disintegrating solution; admitting a heating agent into the interior of the mass and subjecting the mass to the action of the heating agent until the mass is cooked; then draining off and condensing said solution; then admitting compressed air into the container above said mass to thereby create a pressure upon the mass in excess of that of the heating agent and to squeeze out of the mass the remaining surplus solution.

2. The process herein described for the digestion of fibrous material, said process consisting in immersing the material in a disintegrating solution; admitting a heating agent into the interior of the mass and subjecting the mass to the action of the heating agent until the mass is cooked; then draining off and condensing said solution; then

subjecting the mass to pressure to drive out the surplus solution and conducting the same to a condenser.

3. The process herein described for the digestion of fibrous material, said process consisting in immersing the material in a disintegrating solution; admitting a heating agent into the interior of the mass and subjecting the mass to the action of the heating agent until the mass is cooked; then draining off and condensing said solution; then progressively cooling the mass and driving therefrom the surplus solution by successive admission of compressed air above the mass being treated.

4. The process herein described for the digestion of fibrous material, said process consisting in immersing the material in a disintegrating solution; admitting a heating agent into the interior of the mass and subjecting the mass to the action of the heating agent until the mass is cooked; then draining off and condensing said solution; and finally rapidly discharging the mass from the container by means of air-pressure admitted on top of said mass.

5. In apparatus of the character described, a container, a perforated vertical pipe centrally placed therein and other perforated pipes branching from the first pipe, means by which steam may be supplied to said pipes and into the body of the mass being treated, and a condenser connecting with the lower part of the vertical pipe and into which the solution in which the mass is submerged is drained.

6. In apparatus of the character described a container, a perforated vertical pipe centrally placed therein and other perforated pipes branching from the first pipe, means by which steam may be supplied to said pipes and into the body of the mass being treated, and a condenser connecting with the lower part of the vertical pipe and into which the solution in which the mass is submerged is drained, and a compressed air pipe leading into the upper part of the container.

7. In apparatus of the character described, a container, a perforated vertical pipe centrally placed therein and other perforated pipes branching from the first pipe, means by which steam may be supplied to said pipes and into the body of the mass being treated, and a condenser connecting with the lower part of the vertical pipe and into which the solution in which the mass is submerged is drained, said container having a bottom discharge, and a pipe leading compressed air into the upper part of the container and adapted to exert a pressure on the mass of material to rapidly deliver the same through said bottom discharge.

8. The process of digesting wood pulp which consists in cooking the material to

be digested in a closed vessel in the presence of a suitable disintegrating solution by percolating steam through the mass, then turning off the steam and discharging the liquor from the vessel by fluid pressure, then cooling the wood pulp so drained in the vessel by compressed air, and finally discharging the cooled pulp.

In testimony whereof I have hereunto set my hand in the presence of two subscribing 10 witnesses.

JOHN CHARLES WILLIAM STANLEY.
